UNITED STATES PATENT OFFICE.

JOHN A. SWORBEL, OF NEW YORK, N. Y., ASSIGNOR TO DINHOFER BROS., OF NEW YORK, N. Y., A FIRM.

DESIGN FOR A PIN, BADGE, OR LIKE ARTICLE.

52,414.

Specification for Design.

Patented Sept. 10, 1918.

Application filed June 11, 1918. Serial No. 239,486. Term of patent 3½ years.

To all whom it may concern:

Be it known that I, JOHN A. SWORBEL, a citizen of the United States, and a resident of the city of New York, county of Kings, and State of New York, have invented a certain new, original, and ornamental Design for a Pin, Badge or like Article, of which the following is a specification, reference being had to the accompanying drawing, forming part hereof, in which the figure shown is a face view of a pin, badge, or like article, showing my new design.

I claim:

The ornamental design for a pin, badge or like article as shown.

JOHN A. SWORBEL.
